FIG. 2

INVENTOR
HARRY A. BARBER

Patent of Charles H. Sill
Attys.

UNITED STATES PATENT OFFICE

2,597,221

APPARATUS FOR FINISHING ROADS

Harry A. Barber, Aurora, Ill., assignor to Barber-Greene Company, Aurora, Ill., a corporation of Illinois

Application February 4, 1946, Serial No. 645,261

5 Claims. (Cl. 94—46)

1

This invention relates to improvements in a method of and apparatus for finishing roads, and more particularly the apparatus may be exemplified by a machine of the character that travels along a road to be finished, deposits material upon the road, and compresses and smooths the material in order to provide a finished road surface, although the invention may have other uses and purposes as will be apparent to one skilled in the art.

The physical embodiment of the apparatus embodied in the instant invention is an improvement upon road finishing machines of the general character illustrated in Harry H. Barber United States Letters Patent No. 2,138,828 issued December 6, 1938, and Patent No. 2,289,168, issued July 7, 1942. It will be understood, of course, that the instant invention need not be incorporated in a road finishing machine of the exact construction shown in either of those patents.

In the past, many and various types of road finishing machines performing many and various methods of finishing roads have been developed. Usually such machines included some means for dumping material upon a road-bed, means for distributing the dumped material transversely across the road-bed, tamping means for compacting the distributed material, and a screed for leveling and smoothing the compacted material to provide the ultimate road surface. Machines of this character generally travel along the bed of the road being finished and complete the finishing of the road as they continually move forward. Obviously, such machines are rather large in size and costly to manufacture. One of the items adding to the cost of production of such machines is the tamping means and the essential associated mechanism for the proper operation of the tamping elements themselves. The elimination of such tamping means and associated mechanism would materially reduce the cost of such a machine.

With the foregoing in mind, it is an important object of the instant invention to provide a road finishing machine in which tamping means of the character heretofore used have been completely eliminated and replaced by simple, comparatively inexpensive means capable of producing a better result.

Another object of this invention is the provision of a road finishing machine incorporating a material supplier and a screed therebehind, with means disposed between the supplier and screed arranged to continuously strike off ma-

2

terial piled up on the road and tuck that material beneath the screed.

It is also an object of this invention to provide a road finishing machine embodying a material supplying device and a screed, with means disposed between the screed and device operable to compact material piled up on the road with a continuous rubbing action so as to knit the surface material together and maintain it in that condition until acted upon by the screed.

A further feature of the instant invention resides in the provision of a road finishing machine with means disposed between a screed and a material supplier to continually compact material piled up on the road and force feed that material rearwardly underneath the screed.

Another feature of the instant invention resides in the provision of a road finishing machine, with means arranged to provide a continuous compacting action upon the material delivered by the spreader, the material being given a true squeezing action between the means and the road-bed and at the same time being forced or urged beneath the screed.

Still another object of the instant invention is the provision of a road finishing machine embodying a roller pressure feeder between a screed and a spreader, with the roller so situated as to continuously compact material piled up by the spreader and force the material rearwardly beneath the screed.

Also an object of this invention is the provision of a road finishing machine embodying a roller in lieu of tamping means between a screed and a spreader, such roller being so disposed that the forward edge of the screed is substantially tangential to the bottom of the roller.

A further feature of the invention resides in the provision of a road finishing machine including a roller disposed between a screed and a spreader, with a shield or baffle arrangement in such position as to prevent material piled up by the spreader from passing over the top of the roller to the rear side thereof.

It is also an object of this invention to provide a road finishing machine equipped with a roller disposed between a screed and a spreader, the roller being constantly driven at a rate of speed faster than warranted by the forward travel of the machine during operation.

It is also an important object of the present invention to provide a new and novel method of finishing a road in which the action of a roller pressure feeder is utilized.

55 While some of the more salient features,

characteristics and advantages of the instant invention have been above pointed out, others will become apparent from the following disclosures, taken in conjunction with the accompanying drawings, in which:

Figure 1 is a side elevational view, somewhat diagrammatic and with certain parts omitted, of a road finishing machine equipped with means embodying principles of the instant invention and capable of performing the novel method embodied in the instant invention; and

Figure 2 is an enlarged fragmentary vertical sectional view of the structure shown in the left central portion of Figure 1.

As shown on the drawings:

The illustrated embodiment of the instant invention is shown incorporated in a road finishing machine of the self-propelled type that moves constantly forwardly along a road-bed being finished. The machine embodies a pair of crawler tracks 1 which rest upon the road-bed diagrammatically indicated by the line 2. The frame structure of the machine is arranged to provide a receiving platform 3 between the crawler tracks which platform is bottomed by one or more endless conveyors diagrammatically indicated at dotted lines at 4. Another portion of the frame structure defines a suitable base 5 for the support of a power plant 6 such as an internal combustion engine which drives the crawler tracks to move the entire machine or vehicle forwardly.

At the forward end thereof the machine is provided with rollers 7 for engaging the rear tires of a truck carrying road finishing material. The truck dumps this material onto the platform 3 and it is conveyed rearwardly by the moving conveyors 4 and dumped on the road-bed at the rear end of the conveyors in front of a distributor or spreader 8 carried by frame members 9. As seen best in Figure 2, the spreader 8 is preferably in the form of a transversely disposed screw conveyor to laterally spread or distribute the road material across the entire width of the machine.

At the rear of the machine is a screed assembly carried by a pair of side arms pivoted at their forward ends to the frame of the machine as indicated at 11.

The screed assembly includes a screed proper 12 upon which a box-like super-structure 13 is built having vertical front wall 14. A transverse beam 15 extends between the two side arms 10, so that the full weight of the rear ends of these side arms rests upon the screed assembly. Suitable adjustment is provided in the form of one or more adjusting bolts 16 at the rear of the screed assembly the lower ends of which are engaged in pivot slots 11. With reference more particularly to Figure 2, it will be seen that the forward marginal portion of the screed 12 is beveled as indicated at 18, the bevel being upon the upper surface of the screed.

Between the distributor or spreader 8 and the screed 12, a roller or pressure feeder 19 extending substantially the full width of the machine is carried on a shaft 20 mounted in suitable bearing bracket supports. One end of this shaft is also provided with a sprocket wheel 21 which may be engaged by a chain 22 extending over another sprocket wheel 23 carried by an upper horizontal shaft 24. The shaft 24 is driven from still another transverse shaft 25 by way of a sprocket chain or the equivalent carried inside a protective housing 26. The shaft 25 is in turn driven from the prime mover 6 by a sprocket

chain or equivalent mechanism carried in a suitable protective housing 27.

Thus, it will be seen that the prime mover not only propels the entire machine forwardly along the road-bed, but also drives the feeder 19 in a forward direction at the same time. The spreader 8 may also be driven from this prime mover in any suitable manner.

It should be noted that the drive arrangement from the prime mover to the roller or pressure feeder 19 is preferably such that this roller is driven at a faster rate of speed than warranted by the forward travel of the vehicle, so that the undersurface of the roller travels rearwardly at a speed greater than would result from mere contact with the surfacing material. In other words, the roller 19 is driven at a sufficiently fast rate of speed that slippage would result if it were traveling over a surface identical with that upon which the crawler tracks 1 travel.

From the showing in Figure 2, it will be noted that the roller 19 is preferably so disposed as to rest upon the bevel 18 of the forward edge of the screed 12, so that the forward edge of the screed is substantially tangential to the bottom of the roller. Further, the roller is disposed in a socket formed by the projecting forward portion of the screed, the vertical front wall 14 of the screed assembly, and a lower substantially horizontal portion 28 of an arcuate baffle or shield 29. This shield extends upwardly and forwardly above the roller 19 and over the top of the spreader 8 as seen clearly in Figure 2. Obviously, this baffle or shield 29 is for the purpose of preventing road surfacing material from passing over the top of the roller 19 and getting behind the roller. With reference again to Figure 2, it will be seen that the roller 19 takes the place of expensive tamping mechanism formerly used on machines of this character. Not only does it take the place of such mechanism, but the roller 19 actually performs a better and different result than tamping mechanism is capable of performing. In addition, the roller 19 is considerably less expensive to install and operate than tamping mechanism of the type heretofore used.

In operation, as road surfacing material, generally indicated by numeral 30 is deposited upon the road-bed by the conveyors 4, the spreader 8 distributes this material transversely across the road-bed to the width of the machine. Accordingly, this material will pile up adjacent the spreader as indicated in Figure 2. The roller 19 next contacts the material so piled up by the spreader, and as also indicated in this same figure, the roller not only compacts the material but forces it rearwardly beneath the screed 12 so that a finished road surface results as generally indicated at 31. In compacting the material it being recalled that the machine is moving forwardly continuously, the frictional resistance of the road-bed holds the material in place so as to give a true squeezing action between the roller 19 and the road-bed.

It should also be recalled that the roller is traveling at a faster speed than warranted by the forward movement of the vehicle. This faster rate of travel accomplishes several results. It eliminates any hazard of the roller acting as a bulldozer and tending to push the material ahead of it. Further, it helps the roller to strike off material from the pile created by the spreader and tuck that material under the forward edge of the screed. In addition, the roller provides a

rubbing action upon the material in the pile and thus knits the surface material together and maintains it in that condition as it is forced rearwardly under the screed. This provides a smoother finish to the road.

Preferably, the roller 19 is relatively small to eliminate any crushing action akin to that of a steam roller, rather than the desired compacting of the surfacing material.

My novel method of striking off road material from the spreader pile, rubbing the material, compacting it, and force feeding it rearwardly under a screed or other means for smoothing the ultimate road surface is believed to be sufficiently apparent from the foregoing as to warrant no further specific description herein.

From the foregoing, it is apparent that I have provided a novel road finishing apparatus which eliminates one of the most expensive portions of construction of apparatus heretofore known, and which provides an economical substitute for the part eliminated, which substitute performs a different and better result. It will be noted that the surfacing material is not only compacted, but knit together in its upper portion and force fed rearwardly beneath the screed. The entire apparatus is economical to build and operate. It should also be noted that I have provided a new and novel method of finishing a road.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In a road finishing machine, a screed to smooth material on a road-bed as the machine travels along the road-bed, and a pressure feed roller mounted immediately adjacent said screed to compress material and force feed it beneath said screed, and means for rotating said roller at a faster rate of speed than warranted by the rate of travel of the machine.

2. In a road finishing machine that travels along the road being finished, material supplying means, a screed immediately adjacent the rear of said means, and a relatively small roller feeder adjacent said screed, and means to drive the undersurface of said roller rearwardly at a faster speed than warranted by the travel of the machine to cause the roller to rub the material piled up by said means and press it under said

screed thus keeping the surface material knit together.

5 3. In a road finishing machine that travels along the road being finished, material supplying means, a screed to the rear of said means, and a pressure feed roller between the screed and supplying means positioned so that the forward edge of said screed is substantially tangential to the bottom of the roller, and means for rotating the undersurface of said roller rearwardly toward the forward edge of said screed at a velocity higher than the contact velocity.

10 4. In a road finishing machine, means for supplying material to a road-bed as the machine moves forwardly along the road-bed, a screed to the rear of said means, a roller pressure feeder to act on the material between said means and said screed, said feeder being positioned immediately adjacent the forward edge of said screed, and means for rotating the undersurface of said feeder rearwardly at a velocity greater than the contact velocity.

15 5. In a road finishing machine that travels along the road being finished, material supplying means, a screed to the rear of said means, said screed being beveled on its upper forward edge, a pressure feed roller between said screed and said means, and means for rotating the undersurface of said roller rearwardly toward the forward edge of the bevel of said screed at a higher velocity than the contact velocity.

20 30 HARRY A. BARBER.
